UNITED STATES PATENT OFFICE.

WILLIAM WALTER OWEN, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MEASURED-SERVICE TELEPHONE SYSTEM.

Application filed September 7, 1921, Serial No. 499,011. Renewed March 6, 1926.

My invention relates in general to measured service telephone systems, but more particularly to such metering systems intended for use under the complete control 5 of a calling subscriber in extending connections through a variable number of long distance points, and commonly known as zone metering systems.

Among the objects of my invention are 10 to provide means for preventing the talking circuit from being established until the meter controlling equipment is in proper condition to start its charging operation.

Another object of my invention is the 15 provision of means for informing a called subscriber by a distinctive tone when the connection is not yet in condition for conversation, and for removing the tone when the talking circuit is in readiness.

20 In a modification of my invention I have provided means whereby the connection is always immediately cut through when the called subscriber removes his receiver, and wherein the charging equipment simultaneously starts its charging operation.

Other objects are to provide improved and simplified devices for accomplishing the above results.

A few metering systems aiming at some 30 of the above objects have been invented, but it is believed that the system herein disclosed is less expensive, less complicated and is not so restricted in use rendering it more adaptable for commercial use.

35 In the system disclosed herein it is assumed that the community covered by a system is divided arbitrarily into zones of calling, each zone requiring a unit charge. In most cases the unit zone of calling will 40 be all calls in a single exchange or community, while calls from the first zone into an adjoining zone or community require a double or increased rate of charge. Then, if a call is made from one zone through a 45 second zone to a third zone, the charge per each unit of time should be practically three times as great as the unit of charge. The system herein disclosed is not limited in any way to necessitate any particular multiple time arrangement, that is, the arrangement could be such that any decimal proportion might be added when going through 50 an additional exchange.

In the drawings attached hereto I have shown an established connection from one exchange through a second exchange and into a third exchange where the call may then proceed either to the called subscriber in that exchange, or may be extended still further to lines in still other exchanges. 55

It should be understood that each exchange consists of a member of line switches, selectors and connectors, the number depending upon the size of the exchange, also in each exchange there are incoming selectors 60 of a special type in which the incoming trunk lines from other exchanges terminate and also there are a number of selector repeaters in each exchange which are accessible to a certain level or levels of the first 65 selectors and which have access to outgoing trunks to other exchanges. Thus it will be seen, that when a subscriber makes a call to another exchange he first operates his line switch to seize a selector in the usual 70 way and then operates his selector to seize a selector repeater, instead of the regular connector used for local calls. 75

The selector repeater is then operated to 80 pick out an outgoing trunk line to the proper exchange and the next series of impulses are then repeated by the selector repeater to the incoming selector in the other exchange. The incoming selector is then operated to either seize a connector in the other 85 exchange if the call is local or to seize a selector repeater in said other exchange if the call is to be extended to still another exchange.

In the drawings Fig. 1 shows a calling 90 line A in the first exchange having a line switch C individual thereto, which has access to a plurality of selectors such as D. The selector D it will be understood, has access to the regular connectors such as shown at H (Fig. 4) from certain levels and also has access to a few selector repeaters one of which is shown at E (Fig. 2) and which in turn has access to trunk lines to other exchanges. The trunk line shown leads to 100 another exchange and terminates there in the special or incoming selector F. (Fig. 3). This selector is very similar to the selector D (Fig. 1) and has access in common 105 with the regular selectors of this second exchange to standard connector switches and

also to the selector repeaters such as G for calls which are to be extended to other exchanges.

The selector repeater G is the same as the selector repeater E (Fig. 2).

In Fig. 4 is shown a selector I of the same type as selector F with the exception that an extra relay has been provided for sending an additional impulse to the mechanism B' (Fig. 3). This selector is shown as having access to a connector H of standard type which in turn has access to the local lines of the third exchange, the local lines although not shown are of the same type as that shown at substation A, Fig. 1.

Fig. 5 shows a selector repeater very similar to the selector repeater E (Fig. 2), but slightly modified to operate the meter controlling equipment shown in Fig. 6 which is another modification of my invention.

I will now explain more in detail the operations of the switches in the various exchanges when the subscriber A sets up a long distance call to a subscriber either in the second zone or exchange or in a third zone, first describing the operation of the system when using the meter controlling equipment shown in Fig. 2 and then giving a description of the method of operation when Figs. 5 and 6 have been substituted.

When the subscriber at A removes his receiver he operates the line switch C in a well known manner, closing the line circuit and operating line relay 2 which closes a series circuit for switching relay 3 and rotary magnet 4 in series and also prepares a short circuit about relay 3 to the private wiper. Should the first trunk line be busy the ground on the private wiper operates the rotary magnet 4 to step the wipers ahead to an idle trunk. When the idle trunk is reached relay 3 is no longer shorted and energizes to cut off the direct rotary magnet circuit and to switch the line circuit through to the seized selector D (assumed to be the switch seized). Relay 3 also closes one point in the circuit of the meter X which is connected thereby through a fourth wiper 5 to the selector.

As soon as switch D is seized, its line relay 6 energizes over the line circuit and closes the circuit of slow relay 7 which grounds the release trunk to hold switch C on the trunk and prepares a circuit for the vertical magnet 8 and series slow relay 9.

The first series of impulses now operate the relay 6 and cause the vertical magnet 8 to step the wipers to a desired level, in this case assumed to be the level in which outgoing selector repeaters such as E are located. As soon as the switch takes the first vertical step the springs 10 close and relay 11 operates to close the circuit of the rotary magnet 12. As soon as relay 9 falls back after the impulses cease the circuit of rotary

magnet 12 is completed and said magnet operates to step the switch around in search of an idle selector repeater E. Each time magnet 12 operates it opens the circuit of relay 11 which in turn opens the circuit of magnet 12. The ground on the private wiper will again energize relay 11 in case the trunk is busy. This alternate operation of magnet 12 and relay 11 continues until an idle trunk line is reached at which time relay 13, which has heretofore been short circuited by the ground on the private wiper, energizes in series with relay 11, relay 11 being adjusted so as not to energize in series with relay 13.

The operation of relay 13 switches the line circuit through to the wipers and to the seized selector repeater E (Fig. 2) and also closes another point in the circuit of the meter magnet at springs 14. When the line circuit is extended to the selector repeater E a circuit is completed for the line relay 15 thereof in series with the calling line. Relay 15 energizes and in turn operates relay 16 which grounds the release trunk to hold relays 3 and 13 of the line switch C and selector D energized and prepares the circuit of vertical magnet 17 in multiple with the slow relay 18.

As the next series of impulses are sent in relay 15 responds thereto and operates magnet 17 to step the wipers 19, 20, and 21 of the selector repeater to some level in which are located trunk lines leading to the exchange in which it is desired to call. Relay 18 energizes and remains energized during this series of impulses and holds the rotary interrupter relay 22 energized. Relay 22 locks up through springs of rotary magnet 23 and the off normal springs 25 and holds the relay 24 short circuited for the present.

As soon as the impulses of this second digit cease and relay 18 falls back an impulse is sent to the rotary magnet 23, from ground through springs 26, springs 27 and 28 of relay 24, springs 29 and 30 of relay 18, springs 31 of relay 22 and through magnet 23 to battery. Magnet 23 now operates to step the wipers onto the first set of contacts in the selected level, and opens the circuit of relay 22 at springs 32. Relay 22 falls back and opens the circuit of magnet 23 at springs 31. Should the first set of contacts be busy then a circuit would be completed from ground over the private wiper 21, through springs 33 and 34, springs 32, springs 25 and relay 22 to battery. Relay 22 again closes the circuit of magnet 23 to step the wipers to the next set of contacts. This alternate operation of relay 22 and of magnet 23 continues until an idle trunk line is reached when there is no ground present at the private contact, then relay 24, which has been short circuited by this ground on the private wiper, energizes in series with relay 13.

22. Relay 24, upon energizing, opens the circuit of vertical magnet 17, opens the rotary magnet circuit at springs 27 and 28, and completes a locking circuit for itself 5 to the private wiper 21 through springs 33 and 27, and through relay 22 to battery, relay 24 also opens springs 33 and 34 to prevent its being shorted out when ground is supplied to the private by the switch ahead.

10 Relay 24 also closes a bridge at springs 35 across the seized trunk which is assumed to lead to the incoming selector F of the next exchange (Fig. 3). The circuit thus closed for the line relay of said selector F extends 15 from ground through the lower winding of line relay 36, springs 37 and 38, conductor 39, contact 40 and wiper 20, springs 41 of line relay 15, relay 42, upper winding of polarized relay 43, springs 35, wiper 19 and contact 44, conductor 45, springs 46 and 47, and through the upper winding of relay 36 to battery. Relays 36 and 42 energize over this circuit, relay 42 closing the circuit of the polarized winding of relay 43. Relay 25 43 is so constructed that both windings must receive current in the proper direction to energize and does not energize at this time due to the fact that current flows in opposite directions in its two windings. It will be seen that the magnet 48 at selector repeater E is connected through the high resistance 49 and springs 51 and 50 to one side of the line circuit, magnet 48, however, is so adjusted and resistance 49 is of such a value 30 that the magnet does not energize with the normal current flow over the line circuit. Relay 36 of selector F, upon energizing, causes relay 52 to operate to prepare the vertical magnet circuit and also to close a circuit for relay 53 at springs 54. Relay 53 while energizing momentarily closes a circuit from the special battery Y through the magnet 48 and resistance 49 at the selector repeater E as follows: Battery Y through resistance 54, springs 55, 56 and 57, over conductor 39, contact 40, wiper 20, springs 50 and 51, resistance 49, magnet 48 to battery. Current from the battery Y now assists the current flowing from the regular battery through magnet 48 and causes said magnet to operate once to step the wipers of the auxiliary or minor switch B to their first contacts. Should the trunk line 39-45 be of double length for which one unit of 40 charge is required then it would be necessary to have an additional contact grounded on the interrupter, or the relay 53 of the incoming selector associated therewith arranged to send two impulses by adding a relay such as 300 in the manner shown in the selector I, Fig. 4, to operate the magnet 48 two steps.

45 Common to all of the selector repeaters such as E and G of each exchange are a plurality of interrupters or circuit closers M, N, O, P, etc., only the first four of which are shown. These interrupters may be of any desired type or construction. For simplicity I have shown the interrupters mounted on a common shaft the same carrying wipers 58, 59, 60, 61, etc., each wiper passing over a series of contacts one or more of which are grounded. The shaft may be constantly rotated by any suitable means, at a speed that will cause the interrupters 70 to revolve one revolution per minute sending one impulse per minute or faster if desired. Thus it will be seen that if wiper 59 were connected to the meter two impulses per minute would be transmitted to the 75 meter. It will be seen that the manner in which the contacts of the various banks may be grounded would be varied according to the various lengths of the trunk lines through which the connection is being extended thus providing a very flexible arrangement for operating the meter by simply grounding variable numbers of the contacts of the banks associated with the interrupters. The wiper and bank combination R is arranged to serve as an auxiliary switch and operates to complete the connection at the proper time, as will be hereinafter more fully explained. The switch B is operated 80 over the line as the connection is being extended, to choose the particular interrupter which will be used. Thus it will be seen that if the switch B steps one step it will switch the meter conductor from the selector repeater to the interrupter which will operate the meter once every revolution of the shaft and if B steps two steps it will switch to the interrupter which will operate the meter twice every revolution etc.

85 Returning now to the operation of the selector F (Fig. 3), when the next series of impulses are sent from the calling device they operate the line relay 15 of the telephone repeater E (Fig. 2) as for the previous digit. In this case, however, the only effective circuit controlled by the line relay 15 is the circuit of the line relay 36 of the selector F. Each time relay 15 operates it opens a circuit at springs 41 for said line relay 36. Relay 15 also maintains both of the slow relays 16 and 18 operated during impulses. Relay 18 while energized, maintains a short circuit about the two relays 40 42 and 43 in the circuit of the line relay 36 to give more positive operation of said relay. The circuit for line relay 36 extends from ground through its lower winding, springs 37 and 38, conductor 39, contact 40 and wiper 20, springs 41, springs 66 of relay 18, springs 35, wiper 19 and contact 44, conductor 45, springs 46 and 47 and upper winding of relay 36 to battery.

100 Line relay 36 therefore responds to this operation of relay 15 and the selector F is operated in the same manner as was the 105

110

115

120

125

130

135 Common to all of the selector repeaters such as E and G of each exchange are a plurality of interrupters or circuit closers M,

selector D (Fig. 1) to pick out some level of contacts and to select an idle set of contacts in that group. It will be understood that in case the calling subscriber desires 5 to call a local subscriber in this second exchange, then selector F will be operated to seize one of the regular connectors of the system and then the called line. In this case, however, I have assumed that the call 10 is to be extended still farther than this second exchange, and the selector will therefore be operated to seize a selector repeater such as G, a number of which are provided for outgoing calls from each exchange. 15 Therefore as soon as relay 70 of the selector F energizes the relay 68 of the selector repeater G is substituted for the line relay 36 under the control of line relay 15. Relay 68 is therefore controlled through the 20 medium of line relay 15 in response to the impulses of the next flight to step the wipers of selector repeater G to a level of trunks leading to the next exchange, relay 69 operates to ground the release trunk and hold 25 relay 70 of the selector F energized, prepares the circuit of the vertical magnet 71 and relay 72 and also closes the springs 73. The circuit controlled by springs 73 is however, ineffective in this call due to the fact 30 that G has been seized by an incoming selector F and not by local selector such as D and there is no meter conductor extending through the selector F. After relay 72 falls back the rotary magnet circuit is controlled as it was in selector repeater E, to 35 select an idle trunk line in the selected level and to close the talking circuit through to the line relay of the selector I, (Fig. 4). As soon as the line relay 83 of the selector 40 I energizes it closes a circuit for slow relay 82 which in turn closes a circuit for relay 81. This relay is similar to relay 53 of selector F (Fig. 3) and in this case operates to send an impulse of current to the magnet 78 of the selector repeater C from battery Y², and closes the circuit of relay 300 which energizes to send a second impulse from battery Y² to the magnet 78. Magnet 78 therefore operates to step the wiper of the 45 minor switch B' two steps and also repeats the impulses back to the magnet 48 of the selector repeater E (Fig. 2) by closing the springs 84, battery Y' being similar to batteries Y and Y². Magnet 48 (Fig. 2) therefore operates to step the wipers of the 50 minor switch B to their third contacts, it having been assumed that the trunk lines between the first two exchanges are of the one length, and that the trunk between the second and third exchange is of double length. Therefore the switch B will have its wiper connected to the interrupter O, which, will operate to send three impulses from ground each revolution of the shaft. 55 The next series of impulses will operate 60

the selector I of the third exchange in the same manner as selector F was operated except that in this case the selector will be elevated to a level of contacts in which are located connector switches, such as H, 70 which have access to the desired group of local subscribers. As soon as slow series relay 85 falls back relay 87 and magnet 86 will begin operation to automatically select an idle connector, assumed to be the connector H. The next series of impulses will operate the line relay 88 of the connector H which is of standard type to step the wipers to a certain level. Relay 89 puts ground on the release trunk and prepares the circuit of vertical magnet 90 and after the first series of impulses to the switch, relay 91 falls back and prepares the circuit of the rotary magnet 92 and slow relay 93. 75

The next series of impulses will operate 80 relay 88 to cause magnet 92 to step the wipers to the contacts of the desired subscriber's line. If the called line is busy, relay 94 will operate to give the busy signal to the calling party. If the line is idle, 90 however, relay 95 energizes and locks energized and connects ringing current to the called line. 95

As soon as the called subscriber answers 100 a circuit will be completed for the ring-cut-off relay 93 which operates to disconnect ringing current, closes the springs 97 which are ineffective at this time, and cuts the called line through to the back bridge or reversing relay 98. 105

Now when relay 98 energizes it reverses the connections of the line relay 88 to the talking circuit and therefore reverses the flow of current in the upper winding of the bridged electro polarized relay 99 of the selector repeater G (Fig. 3). Relay 99 closes the springs 100 which are ineffective at this time and closes the circuit of the reversing relay 102 to reverse the connection of the line relay 68 to the talking circuit 110 towards the calling subscriber. This reversal of current causes the operation of electro polarized relay 43 of the selector repeater E (Fig. 2) in the same manner as relay 99 was operated. Relay 43, however, 115 in closing its springs 103 closes a point in a circuit for the meter magnet X of the calling line through to the wiper of the minor switch B and thence to the interrupter O (Fig. 2), and closes a point in the circuit of relay 49. It will be seen that as soon as the connection is completed to the called subscriber from the selector repeater E, Fig. 2, that a tone will be connected to the called subscriber's line through springs 111 and 113 to indicate to the called subscriber that a toll call is being made to his line. When the wiper 106 of switch R arrives at its grounded contact relay 49 energizes over the following circuit, springs 108 of relay 120 125 130

43, winding of relay 49, second contact of left bank of switch B, wiper 109, wiper 106 of switch R and its first contact, to ground. Relay 49 energizes over this circuit and locks up through springs 174, at springs 111 removes the tone from the extended line, at springs 64 completes the circuit of the meter X, and at springs 61 and 112 closes the talking circuit.

10 It may be stated at this time that should the wiper 106 be upon its grounded contact at the time relay 43 energized the relay 49 would immediately energize and no tone would be extended to the called subscriber. 15 and the connection would immediately cut through. It will be seen therefore, that as long as conversation continues the magnet X will continue to operate three times per each one half revolution of the shaft until 20 either of the relays 16 or 43 are deenergized by the hanging up of the receiver at the calling or called station.

It will be understood that a call may be thus extended through any number of intermediate zones or exchanges, and that the minor switch of the outgoing selector repeater of the exchange in which the calling subscriber is located, is the only one which is effective to operate the meter and may 25 be connected to any one of a plurality of common interrupters during the progress of a call. Also it will be understood that the interrupters M. N. etc., are common to all the outgoing selector repeaters of an exchange and may be operated continuously or at least as long as any selector repeater is being used. It will be seen that the operating impulses for controlling the minor switch in the originating exchange are repeated back through the various selectors between series of impulses and that the connections from the magnets 48, 78, etc., of the selector repeaters are cut off from the talking circuit by the relays 18 and 72 during the transmission of impulses and by the relays 43 and 99 during conversation.

45 A detailed description having been given of one method of controlling the operation of the meter, it will now be shown how the modification shown in Figs. 5 and 6 may be operated to control the meter.

Upon making a study of Fig. 5 it will be found that the selector V is very similar to selector E, with the exception that the relay 55 49 has been omitted and that relay 243 controls slightly different circuits for controlling the operation of the meter controlling equipment shown in Fig. 6.

60 In the controlling circuit shown and described in Fig. 2 the interrupting equipment was shown common to an exchange and the interrupters were constantly rotated and therefore the tone was required to inform the called subscriber that a call was being 65 extended to his line until the switch cut

thorough or until the interrupter arrived at a certain point, all as has been previously explained.

In this modification, however, this tone is unnecessary as there are provided a plurality of interrupters preselected by switch S, which is individual to the selector, the interrupters are controlled by magnets 301, 302, 303, 304, etc. A switch B² similar to switch B is provided individual to the selector and operates over the same circuit and performs the same function as does switch B, with the exception that it has wipers for connecting any one of a plurality of interrupter sets which may be taken for use.

70 The relays 305-308 are also individual to the selector and are operated in multiple with magnets 301, 302, etc., to close a point in the meter circuit and the particular contact chosen by switch B² through the wiper 75 of the chosen interrupter set.

80 The wipers 353, 357, 355, 352, and 356 are so arranged that no break occurs in moving from one contact until another is engaged for reasons to be hereinafter explained. The 85 operation of switch S is as follows: We will assume that the wipers of switch S are resting on the first contacts of the group of interrupters which are idle, and another switch S also is setting on the first set of contacts; then if the selector associated with the other switch S is operated an operating circuit will be completed from ground, contacts similar to 244, to and through the wiper 90 and contact of its switch S—first position, to magnet 301. The magnet 301 steps the wipers 352, and the wipers shown connected to wiper 352 by a shaft on to the grounded contacts and a circuit is then completed from ground wiper 352 to the first contact 95 of switch S, wiper 353, through break springs 239 to magnet 309, causing the same to move the wipers to the next idle bank contact. It will thus be seen that the 100 switches S always preselect an idle interrupter set.

105 We will now assume that the call has been extended as described in the prior arrangement and that the operating impulses for controlling the switch B² in the originating exchanges are repeated back, all as has been previously explained, and in this case the switch B² will therefore have its wipers resting on its third contacts.

110 When the called subscriber responds the 115 relay 243 energizes the same as was described for relay 43, but in this case the interrupter set having been preselected the connection is allowed to be immediately cut through and the relay 243 closes a circuit from ground, springs 244, conductor 245 to point 349 where the circuit branches to operate relay 305 and magnet 301 in multiple 120 through wipers 346, 366, and their first contacts, it being assumed that the first inter- 125 130

rupter set is idle and the wipers of switch S are resting thereon. Under the condition assumed in this particular call the meter operating circuit may be traced as follows:

5 Ground, wiper 350, conductor 351, third contact of upper bank of switch B², wiper 347, make springs of relay 305, conductor 324, springs 248, springs 238, back over the previously described circuit to the meter X. The

10 magnet 301 interrupts its own circuit at springs 358 and continues to step its associated wipers around until the calling or called subscriber replaces his receiver, which causes the circuit to be opened at relays 215

15 or 243, and thereby cause the disconnection of the meter from the line. Should the disconnection be brought about at a time when the interrupter is off normal the same will have an operating circuit extending from

20 the grounded wiper 352 through the springs 358 for continuing the operation of the interrupter magnet until normal position is reached and the ground removed from the contact of the switch S, making the set

25 available for another call.

I have shown the minor switches B, B' and B² only diagrammatically it being understood that these switches may be of any approved and simple type. As shown these

30 switches are of the type which have a holding dog such as 105, these dogs being disengaged from the ratchet teeth when the release magnets of the associated switches operate to release the switches, thus restoring

35 these switches to normal. The switch S may be of any simple rotary type which always operates in a forward direction having no normal position.

It will also be understood that in case a

40 call is set up from a calling subscriber such as A, through a line switch C, a selector D and a connector H, (Fig. 4) to a subscriber in the same exchange then the meter X will be operated once when the called party answers by the operation of the ring cut off relay 96 of the connector, which connects ground to the meter trunk or fourth conductor and holds the magnet X energized until conversation is terminated. It will

45 also be understood that each line may be provided with a standard type of reverse battery meter, controlled by a polarized relay in series with the line circuit which will register all local calls whenever the reverse

50 battery relay 98 of a local connector energizes. In this case the springs 97 of the connector and the conductor controlled thereby may be omitted and meter X will then register only long distance calls.

60 It will therefore be seen that I have provided a very efficient and simple system of zone metering which requires very little additional equipment and in which most of the additional devices are common to the

65 switches of an exchange.

Having fully described and ascertained the features and aspects of my invention, what I consider to be new and desire to have protected by Letters Patent will be pointed out in the appended claims.

What I claim as my invention is:

1. In a telephone system, calling lines, meters therefor, zones of calling arbitrarily established, a meter controlling device, a plurality of code interrupters accessible to said device each for operating the meter a predetermined number of times per interval of time in accordance with the toll rate for calling into a certain zone or zones, each interrupter having a code starting point, and means made operative during the extension of each call for holding the connection open until the code interrupter selected to charge for that call is in its starting position.

2. In a telephone system, calling lines, meters therefor, zones of calling arbitrarily established, a meter controlling device, a plurality of code interrupters accessible to said device each for operating the meter a predetermined number of times per interval of time in accordance with the toll rate for calling into a certain zone or zones, each interrupter having a code starting point, and means made operative during the extension of each call for holding the connection open until the code interrupter selected to charge for that call is in its starting position, and for giving a distinctive tone to the subscriber while the connection is being so held.

3. In a telephone system calling lines, called lines located in different zones of calling for which zones, different rates of charging are required, a series of code senders each sending a different number of impulses per unit of time, means operated when calling into any zone for selecting the code sender which is arranged to charge for that zone, and means for holding each connection open until the code sender selected is in proper position to start its charging operation.

4. In a telephone system, a calling line, other lines accessible to said calling line over trunk lines of different lengths, a meter for the calling line, a meter controlling device common to the lines, a plurality of code impulse sending devices accessible to said controlling device having a normal position, said device operated during the extension of a call to select the impulse sender which will operate the meter the proper number of times to charge for the particular call, and means associated with the meter controlling device for preventing the connection from being finally established until the impulse senders are in normal position.

5. In a telephone system, subscriber's lines, trunk lines, means for extending a talking connection from a calling line over

- a number of said trunk lines to a called one of said lines, a meter for the calling line, a plurality of meter controlling devices, a plurality of interrupters common to said devices and operated by a common shaft means associated with each trunk line for transmitting one or more impulses to said device as the call is extended thereover, said device responsive to said impulses to connect 5 said meter to one of said interrupters, and means controlled by the called subscriber for causing said meter to be operated at a rate predetermined by the interrupter connected with. 10
- 15 6. In a telephone system, subscriber's lines, trunk lines, means for extending a talking connection from a calling line over a number of said trunk lines to a called one of said lines, a meter for the calling line, a plurality of meter controlling devices, a plurality of interrupters common to said devices and operated by a common shaft, means associated with each trunk line for transmitting one or more impulses to said 20 device as the call is extended thereover, said device responsive to said impulses to connect said meter to one of said interrupters, and means controlled by the called subscriber for causing said meter to be operated at a rate predetermined by the interrupter connected with, and means for preventing the completion of the talking circuit until the interrupters are in the proper position to operate the meters. 25
- 30 7. In a telephone system, a subscriber's line, a meter therefor, trunk lines, automatic switches accessible thereto and through which talking connections may be extended from said line over any number of said trunk lines, an auxiliary switching device associated with each automatic switch, a plurality of interrupters common to said automatic switches, said switching device operated over the various trunk lines 35 as the call is extended thereto to pick out a
- certain one of said interrupters, and means for permitting the selected interrupter to start to operate the meter to charge at a predetermined rate only when said interrupters are in normal position. 40
8. In a telephone system, lines, a meter for each line, automatic switches accessible to any line for extending talking connections therefrom, meter controlling devices common to said switches, means for sending impulses of booster battery from the extended connection, a step by step switch responsive to said impulses to pick out a meter controlling device, and means for preventing closure of the talking circuit until the meter controlling devices are in normal position. 45
9. In a telephone system, a calling line equipped with a meter, a called line, means including trunk lines and serially related automatic switches for interconnecting said lines, a plurality of constantly operating meter operating devices common to said trunk lines, and a relay in one of said automatic switches for completing the talking connection between said lines and for simultaneously starting the calling subscriber's meter to periodically operate at a time contingent on the condition of the meter operating equipment at the time the call is answered. 50
10. In a measured service telephone system, calling and called lines, means for interconnecting said lines and for then signalling the called line, call charging equipment associated with the connection and means operative as a result of the call being answered, operative at a time contingent on the condition of the charging equipment at such time, to complete the talking connection between said lines and to cause the charging equipment to effectively function. 55
- In witness whereof, I hereunto subscribe my name this 25th day of August, A. D. 1921.

WILLIAM WALTER OWEN.
